CAR ROOF CONSTRUCTION

Charles David Bonsall, Pittsburgh, Pa., assignor
to P. H. Murphy Company, New Kensington,
Pa., a corporation of Pennsylvania

Application January 26, 1935, Serial No. 3,547

22 Claims.

(Cl. 108—5)

Heretofore it has been customary to equip box cars with wooden running boards which, in most cases, constituted a dead load on the roof. The principal object of the present invention is to devise a construction wherein the running board becomes an element of the roof structure and as such cooperates with the roof sheets in taking care of the stresses to which the roof as a whole is subjected. Another object is to devise a roof wherein the running board will add little or nothing to the height of the car. Other objects are to provide for the use of lighter gage roof sheets than has been feasible heretofore in a roof of equal strength and to simplify the construction and effect economies in manufacture thereof.

The invention consists principally in making the running board of sheet metal secured to the roof sheets so as to cooperate together in carrying the roof load. It also consists in the combinations and arrangements of parts hereinafter described and claimed.

In the accompanying drawings which form part of this specification and wherein like numerals refer to like parts wherever they occur,

Fig. 1 is a plan view of a part of a car embodying my invention with part of the running board broken away,

Fig. 2 is an end elevation of a car with a part of the running board shown in section,

Fig. 3 is a partial cross-section of the car through a roof rib on the line 3—3 of Fig. 1,

Fig. 4 is a longitudinal central section on the line 4—4 of Fig. 1,

Fig. 5 is an enlarged fragmentary cross-sectional view of a running board saddle and parts welded thereto,

Fig. 6 is a detail vertical section of the end of the running board and adjacent parts on the line 6—6 of Fig. 2,

Figs. 7, 8, 9 and 10 are longitudinal sectional views illustrating divers modifications.

In the construction illustrated in Figs. 1 to 4, the roof comprises wide flat panels 1 at an upper level integrally connected by substantially vertical webs 2 with wide flat panels 3 at a lower level, thus forming a series of alternating ribs and channels whose ends rest on and are secured to the side plates 4 of the car. Roofs of this type, commonly called the neutral axis type, function after the manner of beams with the metal in the upper panels taking care of compression stress, the metal in the lower panels taking care of tension stress and the web portions taking care of the shearing stresses. These stresses are greatest at the ridge, that is, in the region midway be-

tween the side plates that support the roof structure.

In the construction illustrated in Figs. 1 to 4, the ridge portions 5 of the tops of the ribs are made flat and horizontal for a width substantially equal to that of the running board 6; and from these flat metal portions the tops of the ribs slope downwardly toward the eaves, as shown at 7. In this construction, the running board 6 consists of one or more aligned flat sheets or plates 10 of metal that rest flatwise on and are rigidly fastened to the horizontal portions of the roof ribs, preferably by welds 8 that extend continuously along the respective sides of the running board for the full width of the ribs. In this construction, the running board extends continuously across the channels and the portions of the running board above the channels are supported by and secured to suitable brackets or saddles 9 that rest on and are secured to the bottoms of the respective channels, as by welds 10 extending the length of the saddle. The saddle or bracket illustrated in Fig. 5 is a Z-shaped member that may be readily made from sheet metal.

In the construction illustrated in Fig. 4, each roof sheet has a single rib whose width is about half the width of the sheet, successive sheets being welded together along their side margins by continuous welds 11 that are located at the middle of the adjacent channels. With this location of the roof seams, it is quite practicable to secure the sheets together and to the supporting bracket by the same weld, as shown in Fig. 5.

In the construction illustrated in Figs. 4 and 7, the endmost roof panel is at the lower level 35 and the end portion of the running board is supported above said panel by a saddle or bracket 12 that is welded or otherwise secured to the end of the car. This saddle comprises a vertically disposed body portion having a horizontal flange 13 at the top thereof on which the running board rests flatwise and to which it is secured by welding or otherwise. The vertical body portion of the end bracket or saddle has flat bosses 14 struck up therein to bear against 45 the end of the car and space the body portion of said bracket far enough away from the car to permit dirt and cinders to pass between them.

From the foregoing description of the construction illustrated in Figs. 1 to 4, it is obvious that the running board is very light, adds practically nothing to the height of the car and, instead of being a dead load on the roof structure, itself contributes greatly to the strength of such structure. In the channel region, the roof 55

sheets, the running board and the brackets co-operate after the manner of a truss and thereby strengthen the roof. At the same time the portions of the running boards that are welded to the tops of the ribs greatly increase the cross-sectional area of metal in the compression region of the roof, considered as a beam, throughout the region of greatest compressive stress in such roof beam, that is, throughout the full width of the running board measured crosswise of the car; and the metal of the transverse welds further increases such cross-sectional area and is especially effective by reason of its superior strength.

15 The construction illustrated in Fig. 7 is generally similar to that illustrated in Figs. 1 to 4 but differs therefrom principally in making the running board in flanged sections and shaping the sheets so that the seams 15 thereof are at the tops of the ribs instead of at the bottoms of the channels. In this construction, the running boards are secured to the flat tops of the ribs by welds 8 extending along each side thereof and are secured together by welds 16 that also secure together the margins of adjacent sheets.

20 The welds, especially those which extend lengthwise of the roof ribs (that is, crosswise of the car), may be made of an alloy steel, such, for instance, as nickel alloy steel commonly known as stainless steel, whose compressive strength is four or five times as much as the compressive strength of sheet metal of the kind commonly used for car roofs. When it is desired to increase 25 the compressive strength of the roof rib, the edges of the roof sheets and likewise the edges of the running board sections are spaced apart far enough to receive the required amount of metal in the weld to furnish the additional strength, as shown in Fig. 7. The strength of the seam may be increased by building the weld up vertically above the running board; but it is preferable to widen out the weld so as to avoid formation of a rib on the top surface of the running board. In the construction of Fig. 7, 30 the portion of each running board section above the channel has downturned flanges 11 to stiffen the running board. It is also desirable for the ends of the flanges to abut against the sides of the channels and also to be welded thereto. This arrangement not only stiffens the running board itself but affords effective support for the webs of the channels against bending and buckling.

35 In the constructions illustrated in Fig. 8, the flat horizontal middle portions 5 of the roof ribs function as parts of the running board and are connected together by flanged running board sections similar to the sections shown in Fig. 7 but with their flat end portions shortened and spaced apart. In this construction, there are two welds 16 extending longitudinally of the roof ribs and each of them may be built up of stainless steel to increase the strength of the rib for resisting compressive stress.

40 The construction illustrated in Fig. 9 is similar to the construction illustrated in Fig. 8 except that the running board sections are flanged downwardly on the ends as well as on the sides, said end flanges 18 bearing against the sides of the channels and being welded thereto. In this construction, the tops of the running board sections are flush with the tops of the roof ribs and preferably also with the intervening welds. In the particular design of running board section 45 illustrated in Fig. 9, provision is made for a weld

of large sectional area by spacing the upper portion of said section a substantial distance from the sides of the ribs.

5 The construction illustrated in Fig. 10 is the same as the construction illustrated in Fig. 9 with a reinforcing member 19 inside of each rib and extending the full width thereof. This reinforcing member comprises a flat body portion that rests flatwise against the underside of the roof rib and downturned side and end flanges. 10 The end flanges bear against the sides of the rib and are secured thereto, as by welds 20.

15 In order to prevent slipping of the brakemen, the entire surface of the running board is roughened or covered with some suitable material (indicated by the stippling 21). For this purpose, I prefer to paint the upper surface of the running board with a heavy coat of bituminous material and then thoroughly sand it.

20 What I claim is:

1. In a car roof construction of the kind wherein flat-topped ribs alternate with channels, a flat-topped metal running board member extending along the ridge of the car and secured to said ribs, said member being disposed with one face substantially flush with the tops of said ribs.

2. A car roof construction comprising flat-topped ribs of sheet metal alternating with flat-bottomed channels of sheet metal and a sheet metal running board secured flatwise to the tops of said ribs.

3. A car roof construction comprising flat-topped ribs of sheet metal alternating with flat-bottomed channels of sheet metal and a sheet metal running board secured flatwise to the tops of said ribs by continuous welds extending crosswise of the car.

4. A car roof construction comprising flat-topped ribs of sheet metal alternating with flat-bottomed channels of sheet metal and a sheet metal running board secured flatwise to the tops of said ribs by continuous welds extending crosswise of the car and by continuous welds along the sides of said running board.

45 5. In a car roof construction of the kind wherein flat-topped ribs alternate with channels, flat-topped metal running board members extending along the ridge of the car and secured to said ribs by welds extending crosswise of the car, said members being disposed with one face substantially flush with the tops of said ribs.

50 6. In a car roof construction of the kind wherein flat-topped ribs alternate with channels, flat-topped metal running board members extending along the ridge of the car and secured to said ribs by welds disposed crosswise of the car, said members being disposed with one face substantially flush with the tops of said ribs, said welds consisting of added metal of sufficient cross-section to materially increase the compressive strength of the tops of the ribs.

55 7. A car roof construction comprising ribs alternating with channels, the middle portion of the ribs having horizontal tops, and sheet metal running board sections spanning the channels with their ends secured to said ribs and with downturned side flanges extending over the channels.

60 8. A car roof construction comprising ribs alternating with channels, the middle portion of the ribs having horizontal tops, and sheet metal running board sections spanning from rib to rib with their ends secured together and to the tops of said ribs by welds of added metal of 70

- sufficient width to materially increase the compressive strength of the ribs.
9. A car roof comprising ribs alternating with channels, the middle portion of each rib having a horizontal top constituting part of the running board, and metal running board sections substantially flush with the tops of the ribs and rigidly secured to the side walls of the ribs.
10. A car roof comprising ribs alternating with channels, the middle portion of each rib having a horizontal top constituting part of the running board and metal running board sections substantially flush with the tops of the ribs and rigidly secured to the side walls of the ribs and rib reinforcing members of sheet metal disposed flatwise against the under surface of the ribs with their ends provided with down-turned flanges which are welded to the sides of the ribs.
11. In a car roof construction of the kind wherein flat-topped ribs alternate with channels, flat-topped sheet metal running board members having down-turned flanges at their ends which are welded to the sides of said ribs with the tops of said sections substantially flush with the tops of said ribs so as to constitute therewith a continuous running board.
12. In a car roof construction of the kind wherein flat-topped ribs alternate with channels, flat-topped sheet metal running board members having down-turned flanges at their sides and ends, the end flanges being welded to the sides of said ribs with the tops of said sections substantially flush with the tops of said ribs so as to constitute therewith a continuous running board.
13. In a car roof construction of the kind wherein flat-topped ribs alternate with channels, flat-topped sheet metal running board members having down-turned flanges at their ends which are secured by continuous welds to the sides of said ribs with the tops of said sections substantially flush with the tops of said ribs so as to constitute therewith a continuous running board, and an anti-slipping surfacing on said running board.
14. In a car roof construction of the kind wherein flat-topped ribs alternate with channels, flat-topped sheet metal running board members having down-turned flanges at their ends which are secured by continuous welds to the sides of said ribs with the tops of said sections substantially flush with the tops of said ribs so as to constitute therewith a continuous running board, the upper portions of said flanges being spaced from said ribs far enough to receive sufficient weld metal to materially increase the compressive strength of the ribs.
15. A car roof construction comprising flat-topped ribs alternating with flat-bottom channels, said ribs having horizontal portions at the middle thereof, and a sheet metal running board whose side margins are secured to said horizontal portions by continuous welds.
16. A car roof construction comprising flat-topped ribs alternating with flat-bottomed channels, said ribs having horizontal portions at the middle thereof, a sheet metal running board, longitudinal welds uniting the side margins of said running board to said horizontal portions and transverse welds uniting said running board to the side margins of said ribs.
17. A car roof construction comprising flat-topped ribs alternating with flat-bottomed channels, said ribs having horizontal portions at the middle thereof, and a continuous sheet metal running board resting flatwise on said horizontal portions and whose side margins are secured to said horizontal portions by continuous welds, and a bracket welded to the bottom of each channel and constituting a support for said running board.
18. A car roof construction comprising flat-topped ribs alternating with flat-bottomed channels, said ribs having horizontal portions at the middle thereof, and a sheet metal running board whose side margins are secured to said horizontal portions by continuous welds, a running board saddle welded to the bottom of each channel and an end running board saddle on the end of the car with means for spacing the body of the saddle from said end.
19. The combination with a car roof, wherein panels at an upper level alternate with panels at a lower level with the endmost panels at the lower level, of a running board and metal supports for the ends thereof, said end supports having a vertical body portion with bosses constituting means for spacing same away from the end of the car.
20. The combination with a car roof, wherein panels at an upper level alternate with panels at a lower level with the endmost panels at the lower level, of a sheet metal running board and supports for the ends thereof, the portion of the running board beyond the endmost upper panel having downturned marginal flanges.
21. The combination with a car roof, wherein panels at an upper level alternate with panels at a lower level, with the endmost panels at the lower level, of a sheet metal running board and metal supports for the ends thereof, the portion of the running board beyond the endmost upper panel having downturned side flanges and said end supports having a vertical body portion with bosses constituting means for spacing same away from the end of the car.
22. The combination with a car roof wherein panels at an upper level alternate with panels at a lower level, with the endmost panels at the lower level, of a sheet metal running board and metal supports for the ends thereof, the portion of the running board beyond the endmost upper panel having downturned side and end flanges and said end supports having a vertical body portion with bosses constituting means for spacing same away from the end of the car.

CHARLES DAVID BONSALL.
